DESIGN FOR AN OLLA COVER

Edward L. Roberts and Aubrey V. Dennison,
Los Angeles, Calif.

Application July 16, 1934, Serial No. 52,606

Term of patent 7 years

To all whom it may concern:

Be it known that we, EDWARD L. ROBERTS and AUBREY V. DENNISON, citizens of the United States, residing at Los Angeles, in the county of Los Angeles and State of California, have invented a new, original, and ornamental Design for Olla Covers, of which the following is a specification, reference being had to the accompanying drawing, forming part thereof.

Fig. 1 is a front elevation of the article showing our design.

Fig. 2 is a plan of the same partly broken away to show in section as on line 2—2, Fig. 1.

We claim:

The ornamental design for an olla cover, as shown and described.

EDWARD L. ROBERTS.
AUBREY V. DENNISON.
